DESIGN FOR A DISPLAY SIGN FOR BOTTLED PRODUCTS

Grant W. Roberts, Baltimore, Md.

Application April 27, 1933. Serial No. 47,916

Term of patent 3½ years

To all whom it may concern:

Be it known that I, GRANT W. ROBERTS, a citizen of the United States, residing in the city of Baltimore, and State of Maryland, have invented a certain new, original, and ornamental Design for a Display Sign for Bottle Products, of which the following is a specification, reference being had to the accompanying drawing, forming part thereof.

The bottles shown in the drawing may be dummies and form a permanent part of the design.

I claim:

The ornamental design for a display sign for bottled products, as shown and described.

GRANT W. ROBERTS.
